UNITED STATES PATENT OFFICE.

JAMES W. INGLE, OF DAYTON, OHIO, ASSIGNOR OF ONE-HALF TO THOMAS V. MAXEDON,
OF CINCINNATI, OHIO.

AMOUNT-INDICATOR FOR CREDIT-CHECKS AND CASH.

1,238,712.

Specification of Letters Patent.

Patented Aug. 28, 1917.

Original application filed June 17, 1912, Serial No. 704,247. Divided and this application filed October 10, 1914. Serial No. 866,420.

To all whom it may concern:

Be it known that I, JAMES W. INGLE, a citizen of the United States, residing at Dayton, in the county of Montgomery and State 5 of Ohio, have invented new and useful Improvements in Amount-Indicators for Credit-Checks and Cash, of which the following is a specification.

My invention relates to amount indicating devices, but more specifically to such as are employed in connection with receptacles for money and checks representing money. By a requirement for division, the remaining portion of my invention can be 15 found in application Serial No. 704,247, and of date June 17, 1912.

The object of my invention is to provide an automatically operated amount indicator, adapted to bring to view any numerical character from 0 to any suitable number, as 200 or \$2.50, inclusive, as a final resultant of any number of additions to, or subtractions from, any suitable initial amount contained in any suitable receptacle 25 used in connection therewith, thereby overcoming the necessity of keeping books to obtain said resultant.

I accomplish the aforesaid object by means of the mechanism described in the following 30 specification and illustrated in the accompanying drawings in which like reference characters represent like parts in all figures.

Figure 1 is a cross-section of the register on the line *a—a* in Fig. 2, with certain parts 35 eliminated and certain other parts represented in side elevation in order to best illustrate those parts intended to be shown in this figure.

Fig. 2 is a longitudinal section taken vertically on the line *b—b*, as shown in Fig. 1., certain parts being eliminated and certain other parts being shown in side elevation rather than in cross-section, thereby showing them to better advantage.

Fig. 3 is a longitudinal section taken vertically through one of the jam-screws employed in certain parts of my invention.

Fig. 4 is a detached portion of my registering-tape, showing the perforations along 50 the margins thereof and also amount-indicating characters displayed thereon.

Since certain parts of my invention are duplications of other similar parts having

exactly the same operation, it is not thought necessary to apply reference characters to 55 but one of such sets of parts.

1 is the drive-wheel of my registering-tape. 2 is the axle on which said wheel oscillates. 115 is a double row of studs running entirely around the tape-bearing face 60 of said drive-wheel. 3 and 4 are cylindrical studs projecting laterally from the rim of said drive wheel. 5 and 6 are cylindrical studs projecting from the sides of the key-bars 11 and 12. 7 and 8 are pawls pivotally 65 attached to the sides of said key-bars by means of jam-screws 9 and 10. 93 and 94 are thumb-keys on the ends of said key-bars. 13 is a perforation in the rear end of each one of said key-bars, one of which perforations alines with a similar perforation 70 in the upper end of the pay-out lever 28, and the other one alines with a similar perforation in the lower end of the in-take lever 24, through which perforations pass jam-screws, 75 as per 10¹ Fig. 3, pivotally connecting said ends of said levers. 14 and 15 are two guide or slack wheels, one on one side and the other on the other side of said registering-tape drive-wheel and employed to press said 80 tape around and confine it more closely to said drive wheel. 16 is the registering-tape one end of which is detachably attached to spool 18, and the other in like manner to spool 21¹. 19 is the axle on which spool 18 85 revolves. 20 and 21 are numerals placed on said registering-tape to indicate the total cash value of credit checks or cash in the dollar tube at the time either is brought to view on said registering-tape. 22 and 23 90 are bifurcated supports for said registering-tape spools.

59 is a shoulder on the jam-screws against which the washer 60 presses. By means of this mechanism the pawls 7 and 8 and other 95 parts pivoted on these jam-screws are given a free and easy movement and are at the same time held firmly thereon. 61 is a lock-nut which presses against the part, as key-bars 11 and 12, through which these jam-screws screw and prevents said screws from becoming loose. 62 is a horizontal support and bearing means for the axle 2 on which the registering-tape drive-wheels turn, and also for the axles 95 and 96 on which the 100 guide wheels 14 and 15 respectively revolve.

63 is a horizontal support and bearing means for the axle 19 on which the tape spool 18 revolves, the axle for the tape spool 21 having a similar support and bearing means. 5 64 is a drive-pulley attached to the tape spool 18. 65 is a round slip-belt mounted on said pulley and also on a similar pulley 66 attached to, and driven by, said registering-tape drive-wheel 1, said pulleys having 10 cut therearound belt grooves into which said slip-belt works, said belt thereby being prevented from slipping off of said pulley. A similar slip-belt 73 is also mounted on said pulley 66 and also on pulley 72 in the 15 opposite direction from pulley 64, which pulley 72 is a drive-pulley for the tape spool 21 and has cut therearound a similar belt groove to those above mentioned. These slip-belts being driven by the registering-tape drive-wheel 1 and they in turn driving the tape-spools on whose pulleys they are mounted, any movement of the registering-tape drive-wheel in either direction will produce a similar movement and in the same 20 direction to that of said registering-tape drive-wheel. By this mechanism the registering-tape is wound on one of said spools at the same time it is unwound from the other. In case one of these spools takes up 25 the tape faster than it is fed out by the registering-tape drive-wheel, the slipping of the belt on the pulley of said tape spool prevents the locking of the registering-tape mechanism. In case one of these spools feeds out 30 the registering-tape faster than the registering-tape drive-wheel takes it up, what little slack is in this way produced in said tape is taken up by the elasticity of the belt itself, which in this instance appears to be wound 35 more loosely on its spool than it should be. It is to be noted in this connection that there is a double row of short studs projecting from and running entirely around the tape-bearing face of the registering-tape drive-wheel which register with and fit into perforations running along both margins of 45 said tape, thereby insuring steadiness and exactness in the reciprocating movement of said tape. 68 is a beveled drive-cogwheel 50 mounted on the axle 2 which it drives independently of the action of the key-bars on the registering-tape drive-wheel 1. 69 is a beveled cogwheel meshing with said cogwheel 68 when brought into connection 55 therewith, said wheel 69 being securely attached to the lower end of the vertically-disposed rod 70 which extends upward through circular bearings in the parallel supports 75 and 76 to a point near the top 60 plate of my invention, at which point it connects with the detachable crank or key 74. By means of this last described mechanism, a turn on said crank or key one way or the other will operate the registering-tape 65 mechanism independently of the action of said key-bars. To do this the rod 70 is pressed downward until the cogwheel 69 meshes with the cogwheel 68, the push-spring 71 mounted thereon returning said rod to its normal position after the downward pressure thereon is removed therefrom, said spring having its upper end attached to said rod and its lower end resting and revolving on the upper face of the horizontal bearing support 76. The above description of parts as shown in Fig. 2 applies to those parts constituting one registering system which is indicated by the letter I, which system in its operation is entirely independent of every other similar system, of 70 which there are five, making six in all as shown in the drawing, yet it is to be noted that my invention is not limited to any specific number of these independent systems, but that there can be as many of them as are 75 needed for any given purpose. As shown by the drawing, these several similar systems are indicated by the letters I, J, K, L, M and N. It is to be noted also that each guide wheel, each registering-tape drive-wheel and 80 each tape spool revolves on its axle. Each of these independent systems having similar parts, similar construction, and similar functions and operations, a description of one is practically a description of all. 109 is the 85 visible portion of the registering tape of one of the several independent registering systems of my invention, on which visible portions are displayed the numerals, as 20 and 21 or other characters indicating the 90 various amounts, as of dollars and cents, that may be found at any time in each tube from nothing up to as large amount as any one tube will hold of the denomination 95 placed in that tube. 105

Having thus described my invention by illustrations and in detail, I will now describe it as a working mechanism.

My registering-tape drive-wheel 1, which is the drive-wheel of my registering system 110 I, is operated by the pawls 7 and 8 attached to the key-bars 12 and 11 respectively. When the key-bar 12 is pushed inward, the inner face of pawl 7 engages stud 3 and pushes it inward and thereby revolving the 115 registering-tape drive-wheel 1 by so much. As said key-bar comes back to a normal position, the opposite face of said pawl, which face is inclined outward, engages the next stud following stud 3, said pawl being 120 thereby drawn over said stud 3 and brought to a position by the operation of gravity in front of said stud similar to that represented in the drawing as stud 3. Thus, step by step, said drive-wheel is revolved in one 125 direction, said pawl 8 by a similar operation revolving said wheel in the other direction. The different positions of said pawls, one being on the upper and the other being on the lower side of said wheel, makes it 130

necessary for gravity to operate on the inner end of pawl 7 and the outer end of pawl 8, stud 6 holding pawl 7 and stud 5 holding pawl 8 in horizontal positions. Each movement of said wheel as aforesaid brings to view a different numeral on said registering-tape, the numerals brought to view by the operation of said key-bar 12 indicating additions to and those brought to view by said key-bar 11 indicating subtractions from, the contents of any receptacle, as tubes for cash and checks, to which it may be attached. While these numerals in this way do indicate additions and subtractions as aforesaid, they do not indicate the amount, but the resultant, of said additions and subtractions, the difference between the respective numbers giving the amount of each addition and subtraction. To apply this remarkable feature of my invention, we will suppose, in beginning the business for the day, each tube is stocked up with a certain number of checks, all of which have been accurately registered on the registering-tape when deposited, and that tube 48 is a dollar tube and the customer having a dollar check purchased 50 cents worth of goods. If the dollar tube, when the first dollar of the day was deposited in it, had been stocked up with twenty dollars in checks, the depositing of another dollar check brings to view on the registering-tape for the dollar tube the numeral 21¹, which shows that this tube, after the deposit of the aforesaid check, contains \$21.00 in checks instead of \$20.00, as it was before said deposit. But the customer must have 50 cents in checks in change. To do this the clerk places his thumb on key 93 and pushes in key-bar 11, but for the fifty cent tube and not for the dollar tube, and this operation gives the customer 50 cents in change. This operation can be more fully understood by reference to the other application Serial No. 704,247. At the close of the day the figures on the tape total, we will say, \$125.00, and the register was stocked up in the morning with \$65.00 in checks. The difference, \$60.00, indicates the amount of business done and credit given for the day. In stocking up in the morning, all checks and all money are registered in on the registering-tape, and the amount of each noted on a slip of paper kept in a pocket on the end of the left hand till of the drawer, which is for bills and checks. The other tills being for the several denominations of silver money. We will say, in starting for the day, the register shows that it has been stocked up with \$75.00 in money and \$50.00 in credit checks, and these amounts carefully noted on the slip of paper above referred to. A customer comes in with credit checks, which are handled and change made thereon as above explained. A customer comes in with cash, which is han-

dled and change made thereon in the usual manner from the drawer, but all purchases made with cash are carefully registered in on the registering-tape just the same as the credit checks are. At the end of the day 70 the registering-tape totals up \$200.00. The cash is counted and it is found to be \$120.00, which indicates that \$45.00 in cash was taken in for the day. The total of the cash is now taken from the total of the tape and \$80.00 75 remains, which indicates that \$30.00 worth of goods went out for the day on credit checks.

In the normal position of key-bars 11 and 12, the pawls 7 and 8 are held without, that 80 is outside of, the range of engagement with the studs, as 3 and 4, so that, to wind the registering-tape back to 0 in closing for the day, the crank-key 74 is used, thereby saving the wear of the in-take and pay-out mechanism which would otherwise have to be employed in doing so.

Having thus described my invention by illustrations, in detail and as a working mechanism, 90

What I claim is:—

1. In an amount indicator for credit checks and cash, a registering-tape drive-wheel, consisting of a drive-wheel portion and a lateral-projecting hub-shaped portion, 95 said drive-wheel portion having studs projecting radially from the tape-bearing face thereof and studs projecting laterally from the rim thereof, said hub-shaped portion having a cog-toothed lateral edge and 100 also a pulley-like outer surface adapted to the mounting of belts thereon.

2. In an amount indicator for credit checks and cash, a registering-tape drive-wheel having a drive-wheel portion and a 105 laterally projecting hub-shaped portion, said drive-wheel portion having studs projecting radially from the tape-bearing face thereof and studs projecting laterally from the rim thereof, in combination with a registering-tape having marginal perforations therethrough and registering characters thereon mounted on the tape-bearing face of said drive-wheel, spools attached to the ends of said tape, and slip-belts mounted on 110 the hub-shaped portion of said drive-wheel and on the hubs of said spools.

3. In an amount indicator for credit checks and cash, a registering-tape drive-wheel having a drive-wheel portion and a 120 laterally projecting hub-shaped portion, said drive-wheel portion having studs projecting radially from the tape-bearing face thereof and studs projecting laterally from the rim thereof, said hub-shaped portion 125 having a cog-toothed lateral edge, in combination with a registering-tape having marginal perforations therethrough and registering characters thereon mounted on the tape-bearing face of said drive-wheel, spools 130

attached to the ends of said tape, slip-belts mounted on the hub-shaped portion of said drive-wheel and on the hubs of said spools, and means adapted to engage the cog-toothed lateral edge of said drive-wheel and move said tape and said belts in either direction and revolve said spools.

4. In an amount indicator for credit checks and cash, a registering-tape drive-wheel having a drive-wheel portion and a laterally projecting hub-shaped portion, said drive-wheel portion having studs projecting radially from the tape-bearing face thereof and studs projecting laterally from the rim thereof, in combination with a registering-tape having marginal perforations therethrough and registering characters thereon mounted on the tape-bearing face of said drive-wheel, spools attached to the ends of said tape, slip-belts mounted on the hub-shaped portion of said drive-wheel and on the hubs of said spools, an intake key-bar, and intake lever pivotally attached thereto, a pay-out key-bar, a pay-out lever pivotally attached thereto, means attached to said key-bars adapted to engage said laterally projecting studs and cause said drive-wheel to turn and to move said tape and said belts and cause said spools to revolve, the one spool thereby giving out and the other taking up said tape.

5. In an amount indicator for credit checks and cash, the combination of a registering-tape drive-wheel having studs projecting radially from the tape-bearing face thereof and other studs projecting laterally from the rim thereof, an intake key-bar, an intake lever pivotally attached thereto, a pay-out key-bar, a pay-out lever pivotally attached thereto, means attached to said key-bars adapted to engage said laterally projecting studs and rotate said drive-wheel and move said tape, said intake key-bar being adapted to operate said intake lever and simultaneously therewith to rotate said drive-wheel and move said tape one way, said pay-out key-bar being adapted to operate said pay-out lever and simultaneously

therewith to rotate said drive-wheel and move said tape the other way.

6. An amount indicator for credit checks and cash, consisting of a registering-tape drive-wheel having studs projecting radially from the tape-bearing face thereof and other studs projecting laterally from the rim thereof, a registering-tape having marginal perforations therethrough and registering characters thereon mounted on said drive-wheel, spools attached to the ends of said tape, slip-belts mounted on the hub of said drive-wheel and on the hubs of said spools, an intake key-bar, and intake lever pivotally attached thereto, a pay-out key-bar, a pay-out lever pivotally attached thereto, means attached to said key-bars adapted to engage said laterally projecting studs and rotate said drive-wheel, said intake key-bar being adapted to operate said intake lever and simultaneously therewith to rotate said drive-wheel and move said tape one way, said pay-out key-bar being adapted to operate said pay-out lever and simultaneously therewith rotate said drive-wheel and move said tape the other way, in combination with a coin and check handling register, consisting of a plurality of upright tubes of similar construction and operation, openings in the upper end of each tube the uppermost thereof being adapted to receive said credit checks and cash (coins) into said tube and the lowermost thereof being adapted to receive the upper end of said intake lever, and a discharging slide attached to the lower end of said tube and engaged by the lower end of said pay-out lever.

In testimony whereof I have hereunto set my hand in presence of two subscribing witnesses.

JAMES W. INGLE.
